JAMES J. HOWARD, OF STAMFORD, CONNECTICUT

PISTON RING

Application filed January 16, 1928. Serial No. 247,131.

This invention is an improvement in piston rings, and more particularly in sectional rings.

The usual construction of piston ring is a 5 split ring, with the ends beveled or rabbeted or both, and the ring is placed by spreading it so that it will slip over the piston and into the groove.

This type of ring is only applicable to rings 10 of relatively small cross section. When the ring is thick axially, or wide radially, it is impracticable to place it in this manner, as it will snap under the strain of spreading. Furthermore, distortion results due to the spreading, and the ring when placed does not fit the cylinder exactly, and cutting results.

One of the primary objects of the present invention is the provision of a ring composed 20 of similar sections, whereby to enable the positioning of the ring in the groove of the piston without any spreading operation and with no consequent distortion of the ring.

Another object is the provision of a form of ring suitable for use with light or heavy material, involving no liability to breakage or distortion in the placing thereof.

Another object is the provision of a form 30 of ring, which when inserted will fit the cylinder exactly, and at every point in the circumference of the ring, thereby to provide a perfect seal, without undue wear on the cylinder wall.

With these and other objects in view the invention consists in the construction and 35 novel combination of parts fully described hereinafter, illustrated in the accompanying drawings, and pointed out in the claims appended hereto, it being understood that various changes in the form, proportion, size and minor details of construction within the scope 40 of the claims, may be resorted to without departing from the spirit of the invention.

In the drawings forming a part hereof:—

45 Fig. 1 is a plan view of the improved ring.

Fig. 2 is a section on the line 2—2 of Fig. 1.

Fig. 3 is an end view of the shell in which the sections of the ring are assembled for external turning, and with a ring abutting the end thereof.

Fig. 4 is a plan view of the ring as it appears when inserted in the cylinder.

Fig. 5 is a perspective view of the ring.

In the present embodiment of the invention, the ring which is of the usual suitable 55 material, consists of similar sections 1, each of which is of somewhat greater length than a half circle, and the ends of each section are rabbeted as shown at 2, so that the ends of the sections may lap upon each other, the 60 depth of the rabbets being substantially half the axial width of the ring.

The sections are similar, and the ends are beveled as are also the shoulders formed at the 65 inner ends of the rabbets, so that the end of each section fits the shoulder of the other section, the beveled end and the beveled shoulder being indicated at 3 and 4 respectively.

The improved ring is constructed by first 70 turning a continuous ring about an eighth of an inch greater in diameter than the cylinder bore, into which the ring is designed to fit. As for instance, in a three and three-quarter inch cylinder, the ring would be turned to three and seven-eighths inch external diameter. It 75 is then cut in half by rabbeting, which results in a ring in two similar sections, each of which is on an arc of slightly greater radius than that of the cylinder.

A number of rings so constructed, and with 80 the sections assembled, is now inserted in a shell 5 having an internal diameter of one thirty-second of an inch larger than the bore 85 of the cylinder for which the ring is designed. The insertion of the ring sections in the shell puts them under tension, since there is a difference of three thirty-seconds of an inch between the internal diameter of the shell and the external diameter of the ring, and in this condition they are clamped together axially 90 by any suitable means, as for instance washers, and are forced out of the shell in a body. Afterwards the rings are turned to the size 95 of the cylinder bore.

When completed, and released from the washers, the rings assume a slightly oval cross section, the long axis being between the laps, and between the centers of the rabbets at each side of the ring. When the improved 100 ring is inserted in a cylinder, the ring as a

whole assumes an exact circular shape, touching the cylinder wall at every point in its circumference. Because of the shape of the ring and its resiliency, compression at the ends of the long axis decreases the radius in this dimension, with a consequent maximum of increase in a direction of right angles thereto, and an increase gradually diminishing from midway of the section to the ends.

10 It is obvious that the two piece ring can be made in any reasonable thickness, and in any reasonable or practical width, and it can be placed in a cylinder without liability of breakage, and without liability to any permanent distortion. With the improved ring there is a seal as perfect as possible, and the wear of the cylinder is uniform.

15 Because of the waste in material in forming the rabbets, that is in separating the ring into two parts, it will probably be advisable in practice to make the improved ring out of two rings instead of out of one, that is a continuous ring for each section. In this case it will be obvious that the ring will be constructed by first turning two continuous rings, and cutting each to shape.

20 What is claimed as new is:—

25 1. A piston ring having an external circumference corresponding in length to the length of the internal circumference of the cylinder for which it is designed, slightly elliptical in contour, and composed of similar sections, lapping at their ends, the laps being at the ends of the long axis.

30 2. A piston ring having an external circumference corresponding in length to the length of the internal circumference of the cylinder for which it is designed and slightly elliptical in contour, the ring composed of similar sections, the ends of the sections rabbeted in the plane of the ring to lap, the ends of the long axis of the ring being midway of the laps.

35 3. A piston ring composed of similar sections rabbeted to lap at their ends, each section formed on an arc of slightly greater radius than that of the cylinder, so that the complete ring is slightly elliptical with the long axis between the rabbeted ends.

40 4. A piston ring composed of similar sections rabbeted to lap at their ends, each section formed on an arc of slightly greater radius than that of the cylinder, so that the complete ring is slightly elliptical with the long axis between the rabbeted ends, and with the ends of the long axis midway of the rabbets.

45 5. A piston ring of oval contour having an external circumference corresponding to the internal circumference of the cylinder for which it is designed, said ring composed of similar sections lapping at the ends of the long axis of the completed ring.

60 6. A piston ring composed of similar sections lapping at their ends, said ring having an external circumference corresponding in

length to the length of the internal circumference of the cylinder for which it is designed, and being slightly elliptical in contour.

65 Signed at Stamford, in the county of Fairfield and State of Connecticut, this 26th day of November, A. D. 1927.

JAMES J. HOWARD.
